UNITED STATES PATENT OFFICE.

JESSE D. LYON, OF CINCINNATI, OHIO.

GOLF-BALL MARKER.

1,139,689.

Specification of Letters Patent. Patented May 18, 1915.

Application filed January 31, 1914. Serial No. 815,584.

To all whom it may concern:

Be it known that I, JESSE D. LYON, a citizen of the United States of America, and resident of Cincinnati, county of Hamilton, and State of Ohio, have invented certain new and useful Improvements in Golf-Ball Markers, of which the following is a specification.

My invention relates to golf ball markers of the class in which one mechanism may be utilized by a number of persons to mark the name of each individual upon his golf balls.

An object of my invention is to produce a golf ball marker of the class specified, in which one machine may be quickly put in condition to be used by an individual to mark his name upon a golf ball. This and other objects are attained in the apparatus described in the following specification, and illustrated in the accompanying drawings, in which,

Figure 1 is a fragmental side sectional elevation of a machine embodying my invention. Fig. 2 is a fragmental end elevation of the machine illustrated in Fig. 1. Fig. 3 is a fragmental sectional end view, taken on line 3—3 of Fig. 4. Fig. 4 is a plan view of the device, with the parts occupying the same positions shown in Fig. 3. Figs. 5, 6, 7, 8, 9 and 10 are views illustrating details of my invention.

The device illustrated consists of a base 9, upon which is mounted a ball clamp holder 10, a marking-die operating mechanism 11, upon which a ball marking-die holder 12 is mounted, and a ball clamp operating device 13. The ball clamp consists of two cup-shaped jaws 14 and 15, which are mounted on the ends of two stub shafts 16 and 17, slidingly mounted in bearings 18 and 19, respectively. Standards 20, 21, 22 and 23 are formed on the base, adjacent to the cup-shaped jaws 14 and 15 of the ball clamp, and are adapted to partially embrace the jaws, to form guides for them. Pins 24 and 25 are secured in the bottoms of the jaws 14 and 15, and project into a circular opening 26, formed in the base, between the standards 20 to 23. A circular plate 27 is located in this opening and is provided with two eccentric slots 28 and 29, into which the pins 24 and 25 project. A plate 30 is screwed to the under face of the base, against the plate 27, in order to retain this plate in engagement with the bot-

toms of the clamp jaws 14 and 15, and their pins 24 and 25. A pin 31 extends upwardly from plate 30, into an aperture 32, centrally located in plate 27, and affords a pivot bearing for the plate. By rotating plate 27 in a clockwise direction, see Fig. 4, by means of a handle 33, formed integrally therewith, the two ball clamp jaws 14 and 15 will be caused to move toward each other to clamp a golf ball placed between them, and by rotating the plate 27 in an anti-clockwise direction, they will be moved apart to release the ball.

A forked operating lever 34 is rotatively mounted upon the stub shafts 16 and 17, its ends occupying slots formed in the bearings 18 and 19. This operating lever is extended upwardly to form a handle, having two side members which are spaced apart by a block 35, for the purpose of receiving a die-holder 37. The die-holder carries a pin 38, at its upper end, which engages slots 39, formed in the handle 34, thereby permitting both rotative and reciprocatory movement of the holder in the slots. The bottom of the holder is formed with a slot 40, which is adapted to receive a die 41, bearing the character or characters it is desired to mark upon the golf ball, while intermediate its ends an arc-shaped slide 42 is formed for guiding the die-holder between the two portions of the handle. Pins 43 and 44 are located at each end of the slide to afford means for limiting the rotatory movement of the die-holder. An eccentric 45 is rotatively mounted on each side of the handle 34, in position to contact the pin 38 of the die-holder. A U-shaped eccentric operating handle 46, embracing the end of the handle 34, is formed integrally with the eccentrics, and is adapted to cause their rotation, to press the marking die into the surface of the ball, when handle 46 is brought toward handle 34, as shown in Fig. 2, and to release the pressure of the marking-die, when handle 46 is moved to the position shown in Figs. 3 and 4.

In operation: Handle 34 is first moved to the position shown in Figs. 3 and 4, and a die 41 is inserted in the slot 40. The ball to be marked is slipped into position between the jaws. Handle 33 is now moved in a clockwise direction and the ball is securely clamped between the jaws. The U-shaped eccentric operating handle 46 is

5 moved to force the face of the marking die into engagement with the ball. Handle 34 is now moved upwardly and over to the opposite side of the base, in sweeping arc-like path. In this movement, the die-holder is caused to rock in the slots 39, and the die engages the ball surface in a rolling contact, pressing the type on the die into the surface of the ball.

10 The path described by each type upon the die is in the form of an epicycloidal curve, hence the impression made by the die in the ball surface is clean cut, because each letter in being pressed into and in being withdrawn from the surface of the ball, travels in a direction substantially radial to the sphere, thus avoiding breaking the edges of the impression.

15 Jaws 14 and 15 are equally outwardly flared, so that balls of varying sizes may be placed therein, and when the jaws are moved toward each other, the center of the ball will be brought into alinement with the centers of shafts 16 and 17, which form the 20 axis of rotation of the die holder, and into the plane of rotation of the die.

I claim—

1. In a marking device the combination of 25 a base, a die-operating mechanism pivoted upon the base, a die, means for mounting the die upon the operating mechanism in a plane which crosses the axis of rotation of the operating mechanism, and clamps upon the base adapted coincidentally to bring the center of the article to be marked into the 30 axis of rotation of the operative mechanism and the plane of the die.

2. In a marking device the combination of 35 a base, a die-operating mechanism pivoted upon the base, a die, means for mounting the die upon the operating mechanism in a plane at right angles to the axis of rotation of the operating mechanism, and clamps upon the base adapted coincidentally to bring the center of the article to be marked into the 40 axis of rotation of the operative mechanism and the plane of the die.

3. In a ball marking device the combination of 45 a base, two longitudinal pivot shafts upon the base, a die-operating mechanism journaled upon the pivot shafts, a clamping

50 jaw mounted reciprocally upon each pivot shaft, a die mounted upon the operating mechanism, and a handle adapted to reciprocate the jaws upon the pivot shafts.

4. In a ball marking device the combination of a base, two longitudinal pivot shafts upon the base, a die-operating mechanism journaled upon the pivot shafts, a clamping jaw mounted reciprocally upon each 55 pivot shaft, each jaw being flared so as to bring the diameters of balls of varying sizes into alinement with the axis of the pivot shafts when the ball is clamped between the jaws, a die mounted upon the operating 60 mechanism, and a handle adapted to reciprocate the jaws upon the pivot shafts.

5. In a ball marking device the combination of a base, two longitudinal pivot shafts upon the base, a die-operating mechanism 70 journaled upon the pivot shafts, a clamping jaw mounted reciprocally upon each pivot shaft, a die mounted upon the operating mechanism in a plane at right angles to the axis of the pivot shafts, and a handle 75 adapted to reciprocate the jaws upon the pivot shafts.

6. In a ball marking device the combination of aligned shafts, ball-clamping jaws mounted upon the shafts and adapted to bring a diameter of a ball placed between them into the axis of the shafts, a die, means for mounting the die in a plane at right angles to the axis of the shaft, and means for causing relative rotation of the die and 85 the clamping jaws to roll the die over the surface of the ball.

7. A ball marking device comprising a base, a marking die rotatively mounted on the base and adapted to move in a plane, and a ball clamp mounted on the base and adapted to move a ball located therein, so that its equator will lie in the plane of rotation of the marking die.

In testimony whereof I have hereunto 95 subscribed my name this 24th day of January, 1914.

JESSE D. LYON.
